NERI TERRY, OF HARDISTY, ALBERTA, CANADA, ASSIGNOR OF ONE-HALF TO JOHN G. SCHULER, OF HARDISTY, ALBERTA, CANADA.

GRAIN-CAR DOOR.

1,216,013.

Specification of Letters Patent. Patented Feb. 13, 1917.

Application filed April 18, 1916. Serial No. 91,998.

To all whom it may concern:

Be it known that I, NERI TERRY, a citizen of Canada, a resident of Hardisty, in the Province of Alberta, Canada, have invented 5 a new and Improved Grain-Car Door, of which the following is a full, clear, and exact description.

My invention relates to freight cars generally termed grain cars, although useful 10 for carrying other loose material.

An object of the invention is to provide an improved grain door or auxiliary door at the inside of the main door so constructed and arranged as to provide for the ready release of the lower section of the door, notwithstanding the pressure of the loose material against the door.

A further object of the invention is to provide a grain door of the class referred 20 to that may be moved to a position beneath the roof of the car when not in use, the door and its appurtenances being so arranged that no elements will project at the doorway to offer obstruction or interference when 25 the car is unloaded.

The invention will be particularly explained in the specific description following.

Reference is to be had to the accompanying drawings forming a part of this specification in which similar reference characters indicate corresponding parts in all the views.

Figure 1 is a fragmentary side view of a 35 freight car showing my improved grain door in the lowered position at the door opening;

Fig. 2 is a longitudinal vertical section on the line 2—2, Fig. 3;

Fig. 3 is a transverse vertical section;

Fig. 4 is a detail front view showing a portion of my improved grain door;

Fig. 5 is a detail in horizontal section on the line 5—5, Fig. 3.

The invention is applicable to any ordinary box car 10 having a door opening, or 45 openings, 11, and equipped with any ordinary car door 12, here shown as provided with hangers 13 traveling on a top rail 14 and with rollers 15 at the bottom traveling on a rail 16.

The improved grain door is designated generally by the numeral 17 and the lower section 18 thereof is hinged at its upper edge to the upper section by hinges 19, which

are on the front of the said grain door so that the hinge joints break in an inward direction, that is, in a way to permit the lower section 18 to swing outwardly through the door opening 11 as indicated in dotted lines 60 at the left of Fig. 3.

The door 17 is flexible being formed of slats 20 connected by hinges 21 disposed at the inside of the door to break in an outward direction, that is to say, in the opposite direction from the hinge 19 connecting the sections. The flexibility thus produced in the door permits of the same being run in guide-ways 23 on the car at each side of the door opening 11. The said guide-ways 23 70 curve at their upper ends and communicate with guides 24 beneath the car roof 22, the said guides 24 overlapping and being disposed one above another so that the respective door openings 11 at opposite sides 75 will be arranged one above another beneath the roof. The guides are formed of suitable inner and outer irons 26, 26^a.

At the lower ends the guide-ways 23 are contracted as at 27 by extending the irons, 80 26, 26^a, toward each other, thereby producing a restricted throat 28 of a size to permit the passage therethrough of the slats 20 of the lower door section 18. The inwardly projecting members 27, however, constitute 85 a stop and rest for members 29 preferably in the form of rollers, which are provided on the sides of the door 17 adjacent to the hinges 19. The arrangement is such that the rollers 29 will be arrested when 90 the hinges 19 are below the throats 28 and thereby permitting the doors to swing outwardly. At the same time, the doors are retained in the guide-ways and prevented from running downwardly through the 95 throats 28.

Below the guides 23, I provide displaceable retainers 30 for the lower door sections, these being in the form of plates, which are displaceable in their own planes in slots or 100 openings formed in the car at the door opening, the said retainers being illustrated as moving between the studding 31 and the facing 32 in Fig. 5. The plates 30 are provided with transverse slots 33, through 105 which pins or bolts 34 pass. Each retaining plate 30 has an arm 35 thereon which also preferably is slotted as at 36, the slots receiving pins or bolts 37.

To operate the retaining plates 30, each 110

arm 35 of the plates 30 at the sides of the doorway 11 is connected with a bellcrank lever 38, fulcrumed as at 39 on the car, and these bellcranks have connections with 5 an operating lever. In the illustrated example, a link 40 extends from one bellcrank lever 38 to one arm of a T-shaped operating lever 41, fulcrumed as at 42 on the car at the inside or the outside according to the 10 build of the car, the other arm of which lever is connected by a short link 43, with a bellcrank lever 44 fulcrumed as at 45 on the inside of the car beneath the roof. A bellcrank lever 46, similar to the lever 44, 15 is provided at the opposite side of the door and fulcrumed as at 47, said bellcranks 44 and 46 being connected by a rod 48 extending above the doorway 11, and the lever 45 is connected with the adjacent bellcrank 38 20 by a link 49. Thus, the operating lever 41, it will be seen, is simply interposed in the link connections between one of the levers 38 and the adjacent upper bellcrank lever 44, while the opposite upper bellcrank 46 25 is directly connected with its bellcrank 38. The rocking of the lever 41 serves thus to withdraw both retainers 30 when it is desired to discharge the grain by permitting the lower door section 18 to swing out- 30 wardly.

Having thus described my invention I claim as new, and desire to secure by Letters Patent:

35 1. The combination of a freight car having a door opening, members on the car at each side of the door opening forming guide-ways extending upwardly beneath the roof of the car, a door movable in said guide-ways, said door being composed of upper 40 and lower sections, the lower section being hinged to the upper section to swing out-

wardly, the members forming the guide-ways constituting stops at the lower ends of said guide-ways, and the said guide-ways at the said stops being in the form of restricted throats, said throats being positioned adjacent to the position of the hinge connection between the door sections when the door is in the lowered position, members on the door adapted to engage and be arrested by 45 said stops, displaceable door retainers on the door at each side of the doorway below the said guide-ways, and means to displace said retainers to permit the lower door section to swing on its hinges. 50

2. The combination with a freight car having a door opening and guide ways at the sides of said opening at the interior of the car and extending upwardly beneath the car roof, of a door movable in said guides and composed of upper and lower sections, the lower sections being hinged to the upper section to swing outwardly through the door opening when the door is in the opened position, co-acting means on the door and in said guide ways to arrest the downward movement of the door when said door is in position for the lower section to swing outwardly, and displaceable retainers on the car at the sides of the door opening below the guideways and complementary thereto to guide the lower door section and prevent movement thereof on its hinges until the said retainers are displaced. 55

In testimony whereof I have signed my name to this specification in the presence of two subscribing witnesses.

NERI TERRY.
